UNITED STATES PATENT OFFICE

2,437,146

ELECTRICAL DISCHARGE DEVICE EMPLOY-
ING A POOL-TYPE CATHODE

Howard E. Zuvers, Scotia, N. Y., assignor to
General Electric Company, a corporation of
New York

Application November 20, 1946, Serial No. 711,144

6 Claims. (Cl. 250—27.5)

1

My invention relates to electric discharge devices employing a pool-type cathode and particularly to an improved baffle construction for devices of this type.

In the design of electric discharge devices having pool-type cathodes, it is a problem to provide a structure which adequately deflects liquid particles originating on the cathode from the region of the anode and which does not increase the arc drop to an unreasonable value. In accordance with an important aspect of my invention, I provide an improved baffle structure which prevents practically all of the liquid particles liberated from the cathode from reaching the anode region. At the same time, the opposition offered to the arc discharge by the baffle is not so great as to increase the arc drop appreciably. The baffle structure is also suitable for functioning as a control electrode.

It is an object of my invention to provide a new and improved electric discharge device of the gas-filled type.

It is a further object of my invention to provide an improved electric discharge device having a pool-type cathode which is characterised in its operation by relative freedom from arc backs, and a reasonably low arc drop.

My invention will be better understood by reference to the following description taken in connection with the accompanying drawing and its scope will be pointed out in the appended claims. In the drawing, the single figure is an elevational view partially in section of an electric discharge device embodying my invention.

Referring now to the drawing I have shown, my invention embodied in an electric discharge device of the ignitron type and including an elongated cylindrical envelope 1 preferably formed of steel. The envelope is closed at its upper end by a header assembly including an anode seal, designated by the numeral 2, for supporting a generally cylindrical anode 3 centrally within the upper end of the envelope. As is well understood, the seal construction supports the anode in insulated relation with respect to the envelope and provides an externally accessible anode terminal designated by the numeral 4. The anode, in accordance with common practice in electric discharge devices of this type, may be formed of graphite.

The opposite end of the cylindrical envelope 1 is closed by a header assembly 5 including a cup-shaped header 6 which is welded to the lower end of the cylinder 1 to form a hermetic seal. The cathode of the device is provided by a pool of con-

2

ducting liquid 7 which to advantage may be mercury. In the operation of devices of this character an arc discharge is established between the surface of the cathode and the anode 3. For this purpose, a starting electrode 8, which in the illustrated embodiment is of the immersion-ignitor type, is provided. The starting electrode is supported from the header in insulated relation with respect thereto by a suitable lead-in seal including an elongated body of glass 9 which is sealed to an eyelet 10 secured in the header 6, and which surrounds a lead-in conductor 11.

As will be readily appreciated by those skilled in the art, considerable difficulty is experienced in providing discharge devices of this character which are relatively free from arc back and, at the same time, have a sufficiently low arc drop to render them satisfactory for heavy current carrying duty. In accordance with an important aspect of this invention, I provide an improved baffle structure or enclosure, which surrounds the region of the cathode in which the starting electrode is immersed. This structure is arranged to intercept practically all liquid particles which are liberated from the cathode during operation of the device, but not to interfere appreciably with the establishment of an arc discharge from the cathode to the anode. As illustrated the baffle structure is supported from the header 6 on a plurality of studs 12, which are supported in insulated relation about the central portion of the header by means of cylindrical insulators 13. These insulators are secured to the header 6 by means of studs 14 which are welded to the inner surface of the header. Three such insulators 13 and mounting studs 12 are employed in the particular embodiment of my invention illustrated in the drawing. The baffle is made up of a plurality of ring-like members 15 which are stacked on the studs 12 and suitably spaced by spacer members 16. The baffles and spacers are formed of a suitable material which may be predominately graphite. The upper end of the generally cylindrical assembling provided by the baffle members 15 is closed by a disk-like member 17 having a marginal position 18 conforming in shape to the ring-like members 15. The stack of baffle members and spacers is secured in assembled relation by nuts 19 threaded on the upper ends of the studs 12 and engaging suitable bosses provided on member 17. The baffle members 15 may be considered as having frusto-conical surface, and the spacing of the members is preferably such that the projections of the individual members on the axis of the envelope 1 are overlapping. In other

words, there is no unobstructed radial path from the interior of the baffle structure to the exterior thereof and all the passages provided by the structure are directed away from the anode. The structure provided by members 15 and 17 may be considered as an inverted cup-shaped louvered baffle.

In order that the baffle structure may be maintained at a suitable voltage with respect to the cathode and, if desired to function as a control electrode, a suitable lead-in conductor 20 is provided. This conductor is sealed through the envelope in insulated relation with respect thereto by a suitable glass bead 21, and is connected at its upper end to the baffle structure by means of a terminal 22 which is assembled in the stack on one of the mounting studs 12. A cylindrical ring 23 positioned within the insulators 13 is secured to the header 6 by suitable straps 24. The ring may be formed of a refractory material such as molybdenum and extends above the cathode surface to prevent impurities collecting on the surface from entering the region of the starting electrode 8. The ring 23 also tends to minimize the motion of the cathode as a result of shock or vibration of the tube envelope.

In operation of the device a cathode spot is formed on the surface of the cathode by passing a current through the electrode 8 which exceeds a critical minimum value. If the voltage impressed on the anode 3 is more positive than the voltage of the cathode 1 by a predetermined amount, an arc discharge is established between the cathode spot and the surface of the anode. When the anode cathode voltage reverses it is essential that the space within the envelope 1 and particularly the region near the anode be deionized rapidly so that an arc will not become established in the inverse direction. The baffle structure which I provide in accordance with my invention prevents liquid particles of mercury from collecting on the anode surface or from accumulating in the region of the anode and as a result deionization takes place quickly and the tendency for arc backs to occur is minimized. The baffle structure is at the same time sufficiently open so that the arc drop is not too high.

While I have described and illustrated a particular embodiment of my invention, it will be obvious to those skilled in the art that changes and modifications may be made without departing from my invention in its broader aspects and I, therefore, aim in the appended claims to cover all such changes and modifications as fall within the true spirit and scope of my invention.

What I claim as new and desire to secure by Letters Patent of the United States is:

1. An electric discharge device including an envelope, a pool-type cathode retained within said envelope, an anode supported within said envelope in insulated relation with respect to said cathode, means for forming a cathode spot on the surface of said cathode, and a baffle structure surrounding said last-mentioned means and comprising a plurality of generally annular members each having a frusto-conical surface, said members being supported in a stack in such mutually spaced relation that the projections of said members on a plane extending longitudinally of the stack are overlapping and a member presenting a substantially continuous transverse surface supported between said stack and said anode.

2. An electric discharge device including an envelope, a pool-type cathode retained within said envelope, an anode supported within said

envelope in insulated relation with respect to said cathode, means for forming cathode spot on the surface of said cathode and a baffle structure surrounding said last-mentioned means and comprising a plurality of apertured baffle members each having a sloping surface, said members being supported in a stack in mutually spaced relation with said surfaces extending outwardly and downwardly, said stack providing a hollow structure opening toward said anode, and means substantially closing the end of said stack facing the anode.

3. An electric discharge device including an envelope, a header for said envelope for retaining a pool-type cathode within said envelope, an anode supported within said envelope in insulated relation with respect to said cathode and in opposed relation to said header and an inverted cup-shaped louvered structure supported on said header.

4. A header assembly for an electric discharge device of the pool-type comprising a metal header, a starting electrode supported from said header in insulated relation thereto, and a hollow baffle structure supported from said header and surrounding said electrode, said baffle being provided with a plurality of passages through the side walls thereof, the walls of said baffle structures having substantial thickness and said passages being so directed downwardly toward said header so that all particles traversing said passages in an outward direction are directed toward said header.

5. An electric discharge device comprising an elongated cylindrical envelope, an anode supported from one end of said envelope, a liquid cathode positioned at the other end of said envelope in insulated relation with respect to said anode, means for forming a cathode spot on the surface of said cathode, a baffle structure interposed between said anode and the region of said cathode including said spot, said baffle structure including a plurality of generally annular members of dished configuration supported in spaced relation and a member at the upper end of the stack providing a substantially continuous surface arranged in opposed relation with respect to the end of said anode, and a lead-in conductor sealed through said envelope and connected with said baffle structure.

6. An electric discharge device comprising an elongated cylindrical envelope, an anode supported from one end of said envelope, a liquid cathode positioned at the other end of said envelope in insulated relation with respect to said anode, means for forming the cathode spot on the surface of said cathode and a hollow cup-like louvered baffle structure interposed between said anode and said cathode with the closed end thereof facing said anode, the side wall of said structure having substantial thickness and provided with a plurality of openings directed away from said anode.
